UNITED STATES PATENT OFFICE.

FRANK HENRY HOBERG AND DAVID WILLIAM HUDSON, OF GREEN BAY,
WISCONSIN.

HYDRAULIC PRESS.

No. 841,150.

Specification of Letters Patent.

Patented Jan. 15, 1907.

Application filed March 28, 1906. Serial No. 308,421.

To all whom it may concern:

Be it known that we, FRANK HENRY HOBERG and DAVID WILLIAM HUDSON, citizens of the United States, residing at Green Bay, 5 county of Brown, and State of Wisconsin, have invented new and useful Improvements in Hydraulic Presses, of which the following is a specification.

Our invention relates to improvements in 10 hydraulic presses, and pertains especially to that class of presses used for letter-press-copying work or for compressing packages of paper preparatory to tying or wrapping them in bundles for shipment.

15 In the following description reference is had to the accompanying drawings, in which—

Figure 1 is a side view of our invention, drawn partially in vertical section, exposing 20 the hydraulic plunger and the storage-chamber. Fig. 2 is a vertical sectional view drawn on the axis of the pump-cylinder. Fig. 3 is a horizontal sectional view drawn on line *y y* of Fig. 2. Fig. 4 is a partial plan view of the 25 lower portion of the machine, drawn on line *x x* of Fig. 1, with the platen removed. Fig. 5 is a detail sectional view of the relief-valve.

Like parts are identified by the same reference characters throughout the several 30 views.

A base 1 supports an upright cylinder 2 and a hollow goosenecked standard 3, which forms the frame of the press, and also provides a chamber 4 for the reception of oil or 35 other fluid 5. A plunger 6, provided with a cup-leather piston 7, operates in the cylinder 2 and carries a table or platen 8, which is lifted on the compression-stroke toward the stationary plate 9, carried by the upper portion 40 of the standard.

10 is a pump-cylinder, to the lower end of which a duct 11 leads from the storage-chamber through a horizontal bed-plate 12 and vertically at 13 to the lower end of the 45 cylinder 15. A ball-valve 15' is located at the end of the cylinder 10 and fitted to a concave seat at the mouth of the passage 13. During the upward stroke of the pump-piston 16 liquid is drawn from the chamber 4 50 through the passages 11 and 13 past the valve 15' into the cylinder, and on the downstroke the liquid in the cylinder is forced outwardly through a passage 18, chamber 19, and passes a valve 20 in a passage 21, when it is deliv-

ered to a vertical passage 22, leading downwardly into the base 1 and along the base to the bottom of the cylinder 2, underneath the cup-leather piston 7. The valve 20 is provided with a stem 22', guided in a suitable socket in a screw-threaded nut 24, the pressure of the valve upon this seat being regulated by this nut and a spring 32 in the upper end of the valve-stem socket.

The liquid in the cylinder 2 is permitted to exhaust after the compressing operation 65 through a passage 25 in the base 1, which passage 25 communicates with a vertical passage 26, extending upwardly in the pump-casting, and then outwardly at 27 and downwardly at 28 to a passage 29, leading to the 70 passage 11 in the bed-plate 12. A valve-stem 30, screw-threaded at 31, controls the flow of the liquid through the horizontal portion 27 and through the exhaust-passage. Where our invention is applied to letter-copying presses, the pump-piston 10 is preferably operated by means of a lever 39, the latter being pivoted at 40 to a post 41, mounted on the bed-plate 12. The lever 35 is provided with a removable extension 42, 80 adapted to fit into a socket in the permanent portion of the lever, as indicated by dotted lines in Fig. 1. The press may, however, be operated by any other form of power, and we preferably provide a relief-valve 85 controlling a passage 46, leading from the cylinder 2 to the chamber 4. This valve is arranged to open with the pressure and is provided with a stem 48, connected with a lever 49, and carries an adjustable weight 50. 90 Whenever the pressure is sufficient on the valve 45 to lift the weight 50, the liquid escapes through the passage 46 into the chamber 4, and thus limits the pressure which can be exerted on the platen 8.

95 It will be observed that the cylinder 2 is beveled outwardly at its upper edge, as indicated at 55, and forms an annular channel around the plunger 6, adapted to receive any liquid which may escape past the cup-leather 7. The liquid in the channel 55 is permitted to flow by gravity back to the chamber 4 through a duct 56.

Having thus described our invention, what we claim as new, and desire to secure by Letters Patent, is—

1. In a device of the described class, the combination with a base; of a hollow goose-

necked standard; a stationary plate carried by said standard; an upright press-cylinder connected with the base; a plunger operating in said cylinder and provided with a platen; a pump having suction and discharge passages for drawing liquid from the standard and discharging the same into the press-cylinder underneath the plunger; and an exhaust-passage leading from the press-cylinder and communicating with the hollow standard; said exhaust-passage having a raised horizontal portion provided with a manually-controlled valve for regulating the flow of liquid into said passage.

15 2. In a device of the described class, the combination of a base; a hollow standard provided with a press-cylinder, mounted on said base; a bed-plate provided with a pump-cylinder, mounted on the base; valved passages communicating through the pump-cylinder between the standard and press-cylinder; and other passages leading from the press-cylinder to the standard independently of the pump-cylinder and provided with a manually-controlled valve.

30 3. In a device of the described class, the combination of a base; a hollow standard provided with a press-cylinder, mounted on said base; a bed-plate provided with a pump-cylinder, mounted on the base; valved passages communicating through the pump-cylinder between the standard and press-cylinder, and other passages leading from the press-cylinder to the standard independently of the pump-cylinder and provided with a manually-controlled valve; said last-mentioned passages being also arranged to lead in part through the base and in part through the bed-plate of the pump-cylinder.

35 40 4. In a device of the described class, the combination with a base having a hollow standard provided with a hydraulic-press cylinder and press mounted thereon; of a set of castings containing a pump-cylinder and coöperating with the base to form passages communicating between the standard and

press-cylinder, and through the pump-cylinder in one direction; one of said passages being independent of the pump-cylinder and provided with a raised horizontal portion; 50 and a manually-operated valve controlling the passage of fluid through the raised portion.

5. In a device of the described class, the combination of a base; a hollow standard provided with a press-cylinder, mounted on said base; a bed-plate provided with a pump-cylinder, mounted on the base; valved passages communicating through the pump-cylinder; and other passages leading from the 60 press-cylinder to the standard independently of the pump-cylinder and provided with a manually-controlled valve; said pump having a piston, a manually-operated lever connected therewith and a removable extension 65 fitted to a socket in said lever.

6. In a device of the described class, the combination of a base; a hollow standard provided with a press-cylinder, mounted on said base; a bed-plate provided with a pump-cylinder, mounted on the base; valved passages communicating through the pump-cylinder between the standard and press-cylinder, and other passages leading from the press-cylinder to the standard independently of the 70 pump-cylinder and provided with a manually-controlled valve; together with a relief-passage leading from the press-cylinder to the standard; a valve controlling said passage; a lever connected with the valve; and an adjustable weight on said lever; said last-mentioned valve being arranged to open with the pressure of the liquid in the press-cylinder and against the pressure of the weight.

In testimony whereof we affix our signatures in the presence of two witnesses.

FRANK HENRY HOBERG.
DAVID WILLIAM HUDSON.
